SELECTOR MECHANISM

Walter T. Lang, Brooklyn, N. Y., assignor to Control Instrument Company, Inc., New York, N. Y., a corporation of New York

Application December 5, 1947, Serial No. 789,994

5 Claims. (Cl. 177—353)

1

This invention relates to improvements in selector mechanisms and has particular reference to a mechanism of the type disclosed in the pending application of D. L. Herr, Serial No. 774,613, filed September 17, 1947, and now issued as Patent No. 2,453,911, dated November 16, 1948.

In said application, automatic selection is made of a predetermined one of a group of control elements which identifies a desired electrical connection to be established and, in response to said selection, transfer elements individual to said connection are then adjusted from inoperative to operative positions and subsequently moved to engage circuit controlling devices which, by said engagement, initiate the establishment of said connection.

The present invention proposes an improved and simplified construction and arrangement of transfer elements wherein the same are rotatively mounted for actuation by selectable control elements to thereby engage circuit controlling elements identified by the particular control elements selected.

The inventive idea involved is capable of receiving a variety of expressions, one of which, for purposes of illustration, is shown in the accompanying drawings; but it is to be expressly understood that said drawings are employed merely for the purpose of illustrating the invention as a whole and not to define the elements thereof; reference being had to the appended claims for this purpose.

In the drawings:

Fig. 1 is a top plan view of a selector mechanism constructed in accordance with the invention;

Fig. 2 is a side elevation thereof;

Fig. 3 is a longitudinal section on the line 3—3 of Fig. 1, and showing parts of the mechanism at an intermediate stage of operation;

Fig. 4 is a vertical transverse section on the line 4—4 of Fig. 3;

Fig. 5 is a horizontal transverse section on the line 5—5 of Fig. 4; and

Fig. 6 is a fragmentary section similar to Fig. 3, but showing the parts in a completely operated position.

The selector mechanism is shown as comprising a base 10 upon one end of which is mounted an insulated terminal panel 11 supporting a plurality of circuit controlling elements 12. These elements may be in the form of stationary terminals, as shown, through which ground potential, for example, is adapted to be connected by an operation of the selector mechanism which will

2

select certain of said terminals for the establishment of circuits (not shown) that are connected to said terminals; or said elements may be spring contacts or micro switches which will accomplish the same function as said terminals.

Standards 13 extend upwardly from said base 10 and at their upper ends support a stationary frame 14 upon which are slidably mounted a plurality of control plates 15 arranged in stacked relation and adapted for individual selection. Each plate 15 is provided therein with terminal identifying media in the form of long and short slots 16 and 17 arranged in rows and each slot being individual to one of said terminals 12. The arrangement is such that when any one of the plates 15 is selected, the long slots 16 therein will not be effective to establish a circuit through the terminals 12 individual to said slots, but said short slots 17 will cause the establishment of such a circuit or circuits through their associated terminals. The plates 15 are removable and replaceable by others having differently arranged identifying media thereon and, when in stacked position on the frame 14, are held thusly, for sliding movement only, by the spring urged guide rollers 18 pivotally mounted on said frame 14 and adapted to be swung to vertical positions when removing and replacing said control plates. Other guide rollers 18a mounted on the upper ends of the standards 13 engage the edges of the plates 15 to aid in guiding their movements.

Mounted on the standards 13 for reciprocable movement between the panel 11 and the stacked control plates 15 is a carrier frame or press member 19 which includes a plurality of spaced, parallel pairs of vertically disposed plates 20 and 21 with the plates of each pair in abutting relation, the plate 21 of each pair having a flange 22 along its upper edge and the plate 20 being provided at spaced intervals with bearing portions 23 (Fig. 5). Each pair of plates 20, 21 provides a support for a plurality of transfer elements generally indicated at 24 and preferably in the form of pins having upper and lower aligned end portions 25 and 26 and an intermediate portion 27 offset from said end portions and made substantially parallel thereto by bending each pin into crank form. Said intermediate portion 27 of each pin is disposed in one of the bearings 23 which provides an axis for the rotative movement of the pin in one direction when the same is actuated by the selection of one of the control plates 15 and consequent engagement of an end of a short slot 17 therein with the upper end 25 of the pin that extends through aligned slots 16, 17 in all of said

plates. The lower ends 26 of all said pins are normally offset from their individual terminals 12, and the lower extremities of said pins, when in normal position, are disposed slightly below the upper ends of said terminals, as shown in Fig. 6. However, upon initiation of the selection of a control plate 15, the frame 19 is first moved upwardly to the position shown in Figs. 2, 3 and 4 to disengage any pin 24 which has been previously adjusted into contact with its terminal 12 to remove ground potential from said terminal which is connected thereto through said pin and frame. The operation of the mechanism is so timed that when said frame 19 attains its uppermost position, it will dwell there for a period sufficient to effect the selection of the desired plate 15 by shifting the same to the position of Fig. 6, with the consequent operation or rotative movement of those pins 24 which extend through short slots 17 in the plate being selected. When the desired plate has been selected, the rotated pin or pins will assume the dotted line position of Fig. 5 in which the lower ends 26 of said pins will be vertically aligned with their respective terminals 12. The frame 19 then moves downwardly to the position of Fig. 6 and stops in this position to engage the rotated pins with said terminals while non-operated pins which extend through long slots 16 in the selected plate will remain in position at the sides of their terminals and out of contact therewith. The material of which the pins are made has sufficient resiliency so that when their lower extremities contact the terminals 12, the pins will flex slightly about the points where they enter the lower ends of the bearings 23 and said pins will not slide in said bearings due to the bend of the pins at said points. Therefore, the pins will firmly engage the terminals to connect ground potentials thereto, and the resiliency of the pins will permit them to assume their normal state when the frame 19 is again raised. When this occurs, any pin which has been rotated by a previous operation will be rotatively restored to its normal position by the spring 28 connecting said pin to the flange 22 of the plate 21 which provides a support for said pin.

The sequence of operation briefly referred to is the same as that disclosed in the aforementioned patent and the controls by which said sequence is obtained may likewise be the same. Said patent describes a control circuit which, in its adaptation to the present disclosure, will first cause the energization of the motor 29 mounted on the base 10 and whose shaft 30 is geared at 31 to a sleeve 32 rotatable with respect to the cam shaft 33 and held in place thereon by the end collars 34. Said sleeve has fixed thereto an external cam 35 engaged by a follower 36 secured to one end of the rock shaft 37 which carries two arms 38 adjacent its ends that are connected to the frame 19. Coil springs 39 on the standards 13 normally urge the frame 19 upwardly so that the follower 36 will engage the high or low portions of the cam 35 at all times. The energization of the motor 29 occurs upon initiation of a selecting operation and the circuit for the motor extends through normally closed contacts of the switch pile 40 associated with said motor, and also through normally closed contacts of one of a series of switch piles 41 each individual to one of the control plates 15. With the frame 19 in its lower position that it assumes upon termination of a previous selecting operation, the follower 36 is engaged with the high portion of the cam 35 and energization of the motor 29 will

cause said high portion to disengage from said follower, whereupon the springs 39 will urge the frame 19 upwardly to the positions of Figs. 2, 3 and 4 to disengage any of the previously operated pins 24 from their terminals 12 and raise all the pins above said terminals, in which position they will be free from rotation under the influence of the control plates 15. Upon said frame reaching its up position, the normally closed switch contacts of the pile 40 are opened by a cam portion 43 on one face of the cam 35 and the motor 29 is thus deenergized, in which condition it remains during the selection of a control plate 15. When the closed switch contacts of said pile 40 are opened by the cam 43, other switch contacts in said pile are closed to establish an energizing circuit for the cam motor 42 through the latter switch contacts and also through the closed contacts of the switch pile 41 individual to the particular control plate to be selected. Therefore, said motor will drive the cam shaft 33 through the gearing 44 to rotate a series of cams 45 on said shaft, each individual to one of the control plates 15. Said cams 45 are provided with internal grooves 46 (Fig. 3) the effective portions of which are radially offset relative to each other so that rotation of said cams will successively control the sliding adjustment of their respective control plates 15 to operative position. This is done by a bellcrank connection 47 between each cam 45 and its control plate, and as long as the normally closed switch contacts of the pile 41 associated with the desired control plate remain in such condition, the circuit for the motor 42 will be maintained and the unwanted control plates will be successively reciprocated. This reciprocation of the latter plates will cause oscillation of certain pins 24, but their movement to operative position will have no effect since they are now in raised position above the terminals 12.

During the rotation of the shaft 33, the cam 45 individual to the desired control plate will sooner or later reach a position where a projection 48 on its periphery will engage a contact 49 of the associated switch pile 41 and thus reverse the positions of the switch contacts therein. This reversal opens the normally closed contacts to break the energizing circuit for the motor 42, whereupon the driven cam shaft 33 comes to rest with the desired control plate in the position of Fig. 6 and with the pins 24 rotated by said plate in their operative or aligned positions relative to the corresponding terminals 12. Said reversal of the switch pile 41 also reestablishes the energizing circuit for the motor 29 which now resumes the rotation of its cam 35 from the point where it was stopped until said cam has lowered the frame 19 to bring the operative pins 24 into contact with their respective terminals 12 to establish the desired circuit connection, whereupon the motor 29 will be stopped by disengagement of the cam portion 43 from the switch pile 40, as described in said patent. As is well understood, clutch or brake mechanisms (not shown) may be utilized to stop the cams 35 and 45 in proper positions upon deenergization of the respective motors 29 and 42.

What is claimed is:

1. In a selector mechanism, a plurality of circuit controlling elements, a group of selectable control elements each individual to certain of said circuit controlling elements, means to select one of said selectable control elements, a plurality of transfer elements having normally inoperative positions relative to said circuit controlling ele-

ments and each comprising a unitary pin having end portions adapted for engagement, respectively, with said control and circuit controlling elements and an intermediate pivotal portion offset from said end portions, and a carrier frame in which said intermediate portions are rotatable by the selection of said control elements and the engagement thereof with the first named end portions of said pins to position their second named end portions for contact with said circuit controlling elements.

2. In a selector mechanism, a plurality of circuit controlling elements, a group of selectable control plates stacked thereabove and each individual to certain of said circuit controlling elements, means to select one of said selectable control elements by moving it relative to the others, a plurality of transfer pins having upper end portions extending through said plates and lower end portions normally in inoperative positions relative to said circuit controlling elements and adapted for engagement therewith following the selection of one of said plates, each of said pins further having an intermediate portion parallel to but offset from said end portions, a movable frame constituting a bearing for said intermediate portions in which certain of said pins are rotated upon selection of one of said plates to locate the lower ends of the latter pins in vertical alignment with certain circuit controlling elements, and means to thereupon move said frame to engage the lower portions of the rotated pins with the aligned circuit controlling elements.

3. In a selector mechanism, a plurality of circuit controlling elements, a group of selectable control plates stacked thereabove and each individual to certain of said circuit controlling elements, means to select one of said selectable control elements by moving it relative to the others, a plurality of transfer pins having upper end portions extending through said plates and lower end portions normally in inoperative positions relative to said circuit controlling elements and adapted for engagement therewith following the selection of one of said plates, each of said pins further having an intermediate portion parallel to but offset from said end portions, a movable frame comprising opposed plates combining to form bearings in which said intermediate portions of the pins are located for the rotation of certain of said pins upon selection of one of said control plates to position the lower end

portions of the rotated pins for contact with associated circuit controlling elements, means to thereupon move said frame to engage said lower ends of the rotated pins with the last named circuit controlling elements, and means connecting one of said frame plates with the rotated pins to restore the latter to normal upon initiation of the selection of another control plate.

4. In a selector mechanism wherein circuits are established through certain of a plurality of circuit controlling elements by the selection of one of a group of control elements individual to said certain circuit controlling elements, the combination of a carrier frame movable relative to said control and circuit controlling elements, and transfer elements each individual to one of said circuit controlling elements and movable with said frame and rotatively supported therein about axes substantially parallel to the movement thereof, said transfer elements having portions operable by said selectable control elements to rotate said transfer elements to positions wherein they will engage the circuit controlling elements upon movement of said carrier frame toward the latter elements.

5. In a selector mechanism wherein circuits are established through certain of a plurality of circuit controlling elements by the selection of one of a group of control elements individual to said certain circuit controlling elements, the combination of a carrier frame movable relative to said control and circuit controlling elements, a plurality of transfer pins each individual to one of said circuit controlling elements and adapted for contact therewith to establish a circuit and each comprising upper and lower end portions, the former of which are engaged by and adapted for actuation by said selectable control elements and the latter end portions being capable of flexing when engaged with one of said circuit controlling elements, each pin further including an intermediate offset portion constituting an axis for the rotation of said pin when the upper end thereof is actuated by a selectable control element, a movable frame in which said intermediate portions of said pins have only rotative movements, and means to move said frame to engage the lower ends of those pins which have been rotated with their respective circuit controlling elements.
